UNITED STATES PATENT OFFICE.

CHARLES P. CASSON, OF NEW YORK, N. Y., ASSIGNOR TO AMERICAN GRAPHOPHONE COMPANY, OF BRIDGEPORT, CONNECTICUT, A CORPORATION OF WEST VIRGINIA.

DESIGN FOR A TALKING-MACHINE CABINET.

51,835.

Specification for Design.

Patented Mar. 5, 1918.

Application filed October 12, 1917. Serial No. 196,334. Term of patent 7 years.

To all whom it may concern:

Be it known that I, CHARLES P. CASSON, a citizen of the United States, and a resident of New York city, have invented a new and ornamental Design for Talking-Machine Cabinets, which is set forth in the accompanying drawing, in which the figure is a perspective view of a talking-machine cabinet illustrating my said design.

I claim—

The design for a talking-machine cabinet substantially as set forth in the accompanying drawing.

In testimony whereof I have signed this specification.

CHARLES P. CASSON.
